United States Patent Office.

SIMEON R. BOLTON AND FRANCIS HOYT, OF PRESCOTT, WISCONSIN.

Letters Patent No. 85,785, dated January 12, 1869.

IMPROVEMENT IN SLED-BRAKES.

The Schedule referred to in these Letters Patent and making part of the same.

To all whom it may concern:

Be it known that we, SIMEON R. BOLTON and FRANCIS HOYT, of Prescott, in the county of Pierce, and State of Wisconsin, have invented a new and valuable Improvement in Sled-Brakes; and we do hereby declare that the following is a full, clear, and exact description of the construction and operation of the same, reference being had to the annexed drawings, making a part of this specification, and to the letters and figures of reference marked thereon.

Figure 1 of the drawings is a representation of a plan view of our sled-brake inverted.

Figure 2 is a side view, and

Figure 3 is a sectional view thereof.

Our invention relates to that class of devices designed to neutralize the force of gravitation upon a sled when moving down-hill, the object being to attach such means to the harness of the team, as will secure the desired object, without the aid of the ordinary hand-brake.

The letter *a* of the drawings represents a guard attached to the side of the sled-runner, and letter *b* is a brace or brake working therein, pivoted to the arm *c*, as shown.

The arm *c* is a part of the tumbling-rod *d*, bent outward, at a suitable distance from the end thereof.

The tumbling-rod *d* is constructed and adjusted in the form and manner shown. It is attached to the lower side of the sled-beam in staples, and extends from side to side of the sled with an arm, *c*, on each end.

At the point *e*, this rod is bent outward, as represented, to form a loop that shall serve the purposes of a lever, for the devices hereinafter mentioned.

The letters *f* are coiled springs, adjusted as shown, and are designed to regulate the movements of said tumbling-rod.

The letter *g* is a rod extending from *e* to the rod *h*, with which it is united in the form of a hinge, or hook and eye, at the point *i*.

The rod *h* extends from the point of its union with rod *g* to the lower end of the neck-yoke lever next mentioned, passing through staples on the lower side of the sled-tongue.

The neck-yoke lever, marked *k* on the drawings, constitutes an important part of our device. The form of its construction, and the mode of its adjustment to the sled-tongue are well shown on the drawings. It is joined with the front end of rod *h*, at its lower end, while its upper end is arranged to receive the ring of the neck-yoke.

The connection with the sled-tongue is formed by passing said tongue through the opening *o*, and fastening it therein by means of a pin, that passes through said tongue from top to bottom, and pivoting it with the lever at the point *r*.

Our device operates as follows, namely:

When the sled, in passing down-hill, presses against the horses, and they begin to "hold back," the upper end of the neck-yoke lever *k* is drawn backward. The lower end is pushed forward then by moving forward the rod *h*, and actuating all the devices connected therewith. The result is, that the braces *a* are forced downward and forward by the arms *b*, and held in the snow or ice on an angle of about forty degrees, more or less, with the sled-runners, and the speed of the sled is at once checked thereby.

It is obvious that by means of the devices herein enumerated and shown, the movements of a sled, in passing a downward grade, may be regulated at will, without the use of a hand-brake, crow's-foot, or other machinery.

What we claim as our invention, and desire to secure by Letters Patent, is—

A sled-brake, having braces *b*, arm, *c*, rods *d*, *g*, and *h*, springs *f*, and guards *a*, in combination with the neck-yoke lever *k*, when constructed and arranged substantially as herein specified.

In testimony that we claim the above, we have hereunto subscribed our names, in the presence of two witnesses.

SIMEON R. BOLTON.
FRANCIS HOYT.
